UNITED STATES PATENT OFFICE.

ALESSANDRO LEATI, OF MILAN, ITALY.

COOKING RANGE.

1,408,811.

Specification of Letters Patent.

Patented Mar. 7, 1922.

Application filed May 3, 1920. Serial No. 378,677.

To all whom it may concern:

Be it known that I, ALESSANDRO LEATI, a subject of the King of Italy, residing at Milan, Italy, have invented new and useful 5 Improvements in Cooking Ranges, of which the following is a specification.

The present invention relates to cooking ranges and has for its object an improved cooking range adapted for any solid fuel, 10 whether in lump or in dust form.

The main features of the invention consist in the rational combination of the various parts and in a special arrangement or valve, by means of which an upward or a 15 downward draught can be obtained at will according as it is or is not desired to utilize the oven arranged in the lower portion, the oven being heated more or less as may be convenient or not being heated at all.

20 In the annexed drawings:

Fig. 1 is a vertical section of the apparatus;

Fig. 2 shows the same apparatus, partly in section and partly in outside view at an 25 angle of 90° with respect to Fig. 1.

The apparatus comprises a lower chamber 1 forming its base, the chamber bottom 2 and sides 3 being preferably in practice lined with good non-conducting material. 30 Inside the chamber 1 a metal, preferably sheet metal, case 4 is provided, whose front 5 is fitted with a door 6. Between the outer chamber 1 and the inner case 4 an empty space is left for the circulation of the hot 35 gases.

On the case or oven 4 an angle collar 7 is mounted, the collar being an easy fit on a cylinder 8 mounted on the base and hinged to an operating ring through members 9. 40 In the collar 7 slots 7' and 7'' are formed.

In the top portion of the oven a circular ceiling 11 is provided, the same being fitted with slots 12 and 12' corresponding to the slots 7' and 7''. In the plate 14 of the cover 45 11 a central aperture 15 is formed which serves to connect the hollow inside space of the cover to the inside of a stove or combustion chamber consisting of a cylindrical sheet metal box 16 and a frame 20 arranged 50 therein on a tripod 19.

In the top portion of the cooking range a water kettle 22 is arranged, whose inlet 23 and outlet 23' may also serve as connections for the piping of a thermosiphon.

55 In the top plate 24 are provided, in the

usual way, apertures fitted with rings 25 and covers 26.

A sliding box or drawer 27 arranged above the oven serves as ash-pit and may also be filled with fuel when the oven is 60 directly heated. A door 28 is provided in the drawer 27.

The smoke stack 29 is connected to the chambers 8 and 1 respectively by means of pipes 30, 31 fitted with swivel dampers 32, 65 33 of which 34, 35, 36, 37 make up the actuating gear.

When it is desired to simultaneously heat the upper portion and the oven, the collar 7 is partly rotated, by means of a handle 70 40 connected at 41 as shown, so as to close the slots 12 and open the slots 12'. Air is then admitted through the door 28 and through the apertures 15, 18, passes through the frame 20 and feeds the combustion at 75 38; the combustion gases accordingly impinge against the upper portion of 24 in the chamber 21, then against the sides of the oven 4 and go through pipe 31 to the stack 29. In that case the swivel damper 80 33 is closed and 32 open.

By bringing the collar 7 into the position shown in Fig. 2, that is to say by so operating it as to open the slots 12 and close the slots 12', and by closing the door 85 28 and opening the top aperture 26, air is let in at 26, gets into the frame 20 where it feeds the combustion and after this enters the chamber 1 through the apertures 18, 15, 12 and finally gets into the pipe 31. 90 In this case the oven, and the oven alone, will be intensely heated.

If, instead, it is desired to heat the top portion alone and not the oven, it will suffice to open the door 28 and the swivel damper 95 33 as indicated with dotted lines in Fig. 1.

Having now particularly described and ascertained the nature of my said invention, and in what manner the same is to be performed, what I claim is:

1. A cooking range comprising a lower chamber, an upper chamber having a central opening in the bottom, an oven in the lower chamber and spaced from the top, bottom and side walls thereof, smoke escape 105 ducts leading from said chambers and each having a damper, a combustion chamber in and spaced from the side wall of said upper chamber, a removable closure for the top of said upper chamber, and means to establish 110

air communication between the bottom of the combustion chamber and the lower chamber and between the latter and the upper chamber at will.

- 5 2. A cooking range comprising a lower chamber, an upper chamber having a central opening in the bottom, an oven in the lower chamber and spaced from the top, bottom and side walls thereof, smoke es-
10 cape ducts leading from said chambers and each having a damper, means to reversely

simultaneously operate said dampers, a combustion chamber in and spaced from the side wall of said upper chamber, a removable closure for the top of said upper chamber, and means to establish air communication between the bottom of the combustion chamber and the lower chamber and between the latter and the upper chamber, at will. 15

In witness whereof I affix my signature. 20

ALESSANDRO LEATI.
